UNITED STATES PATENT OFFICE.

CHARLES P. WATSON, OF YORK, PENNSYLVANIA.

SHELL-FUSE.

SPECIFICATION forming part of Letters Patent No. 792,369, dated June 13, 1905.

Application filed January 5, 1904. Serial No. 187,826.

To all whom it may concern:

Be it known that I, CHARLES P. WATSON, a citizen of the United States, residing at York, in the county of York and State of Pennsylvania, have invented certain new and useful Improvements in Shell-Fuses; and I do hereby declare the following to be a full, clear, and exact description of the invention, such as will enable others skilled in the art to which it applies to make and use the same.

This invention relates to that class of percussion-fuses wherein a barrier adapted to be acted upon by centrifugal force is interposed between the hammer or plunger and the detonating cap, whereby said hammer or plunger is prevented from accidentally coming into contact with said detonating cap; and the principal objects are, first, to simplify and cheapen the cost of production of this type of fuse; second, to insure a positive arming of the parts, and, third, to render said parts less liable to strain and injury from sudden shock or jar either in handling or firing the shell.

Other objects of the invention will become apparent upon a more complete disclosure thereof.

With these objects in view the invention consists, essentially, of the novel construction and peculiar arrangement of the several parts and their general combination, as will be hereinafter fully described, and briefly stated in the claims.

In the drawings, Figure 1 is a longitudinal sectional view of my improved fuse; Fig. 2, an enlarged longitudinal section of the hammer or plunger; Fig. 3, a similar view of the cap-carrying plug; Fig. 4, a plan view of the front end of the hammer or plunger; Fig. 5, a similar view of the cap-carrying plug; and Fig. 6 a perspective view of one of the wings or jaws and the spring for holding them normally closed.

Referring to the several views, the letter *a* indicates the stock, *b* the hammer or plunger, and *c* the cap-carrying plug. The stock is of the usual construction, being provided with the usual flanged head *d* and screw-threads *e*, and is suitably bored to provide a hammer or plunger chamber or recess *f* and a priming chamber *g*. A portion of the inner face of

the recess-wall is screw-threaded to receive a screw-threaded plug *h*, which divides the hammer or plunger chamber from the priming-chamber, as shown in Fig. 1. The inner or rear face of the plug *h* is counterbored to form a recess or chamber *i*, and projecting from the transverse wall of the recess *i* is a boss or hub *j*. The end of the boss or hub is provided with a depression *k*, into which is seated a detonating cap *l*, and leading from the cap *l* is a firing channel or hole *m* communicating with the priming-chamber *g*.

The front end of the hammer or plunger is counterbored to form a recess *n* for the reception of a barrier *p*, consisting of a pair of wings or jaws *q*, *r*, preferably spring-hinged, as shown in Figs. 1 and 2, pivoted to the hammer or plunger. The counterbored end of the hammer or plunger is provided with a firing pin *s*, which projects a slight distance between the jaws or wings. The outer face of each jaw or wing is provided with a small lug or projection *t*, which is arranged to project into the depression *k* and normally hold the wings or jaws in locked position. It will be understood that the normal position of the wings or jaws is closed, as shown in Fig. 4, and it is in this position that they are locked to prevent any possibility of their accidentally assuming an armed position. The locking engagement is maintained by the pressure of a spring *u*, having one end seated in a depression in the stock and the other end seated in a depression in the rear end of the hammer or plunger. The hammer or plunger is provided with one or more longitudinal channels *v*, preferably in its outer surface, which form passages for the escape of the air from in front of the hammer or plunger to the rear thereof, and vice versa, thereby preventing the air-cushioning at either end of said hammer or plunger, which is liable to retard or interfere with the free movement of the hammer or plunger at the instant of shock on firing or on impact. In their normal position it will be seen that the front end of the hammer or plunger is slightly telescoped in the recess or chamber of the cap-carrying plug, and when a shell armed with my improved fuse is fired from a gun the shock will force the hammer or plunger

back against the pressure of the spring w , 5 freeing the wings or jaws from their locked position to the action of the centrifugal force induced by the rapid rotation of the shell, which pressure will gradually exert itself to force said hammer or plunger forward a sufficient distance to allow the boss or hub k to enter between the wings or jaws and hold them in their outward position and the hammer or plunger in an armed position, ready to strike the cap the instant the shell encounters an obstruction, the action of the hammer being sufficiently sensitive to move forward on a shock produced by a glancing blow or by impact at the point or nose.

25 By pivoting the wings or jaws to the hammer or plunger they are relieved from all strain attending the shock received in firing, as said wings or jaws move backward with said hammer or plunger, and as they give additional weight to the hammer or plunger it will be readily seen that a hammer or plunger of required weight can be provided without increasing the size of said hammer or plunger.

30 To insure a gradual return movement of the hammer or plunger from its "setback" position, caused by the shock received in firing, I provide a small stud x , which enters one of the grooves v and tends by frictional contact to slightly retard the movement of the hammer or plunger as it moves forward under the pressure of the spring w , whose length is not sufficient to exert pressure enough to force the hammer or plunger into 35 contact with the cap. The pin also serves to prevent the hammer or plunger from rotary motion in its chamber, and when all of the parts are assembled and in normal position a compact and safe fuse is produced, but one in 40 which the parts will not fail to assume an armed position and when such position is assumed will be extremely sensitive to the slightest shock.

Having thus fully described my invention, 45 what I claim, and desire to secure by Letters Patent, is—

1. In a shell-fuse, the combination with the stock, a hammer or plunger seated therein, said hammer having a recess in its forward 50 end and a firing-pin projecting from said recess, and a plug removably secured within the stock, said plug having a recess in the inner or rear end and a boss or hub carrying a detonating cap, of a pair of wings or jaws pivoted within the recess in the hammer and so arranged that said wings will be acted upon by centrifugal force, and means holding the free ends of the wings in closed position, whereby said hammer is prevented from accidentally contacting with the cap.

55 2. In a shell-fuse, the combination with the stock, a hammer or plunger seated therein, said hammer having a recess in its forward end and a firing-pin projecting from said recess, and a plug removably secured within the

stock, said plug having a recess in its inner or rear end and a boss or hub carrying a detonating cap, of a pair of wings or jaws pivoted within the recess in the hammer, means holding the free ends of the wings in closed position, and means normally locking said wings in their closed position.

3. In a shell-fuse, the combination with the stock, a hammer or plunger seated therein, said hammer having a recess in its forward 75 end and a firing-pin projecting from said recess, and a plug removably secured within the stock, said plug having a recess in its inner or rear end and a boss or hub having a depression in which is fixed a detonating cap, of a pair of spring-hinged wings or jaws pivoted within the recess in the hammer, said jaws being provided with lugs arranged to enter the depression in the boss, whereby the free ends of the wings are normally locked in their 85 closed position.

4. In a shell-fuse, the combination with a suitable stock, a hammer or plunger seated therein, said hammer having a recess in its forward end and a firing-pin projecting from said 90 recess, and a plug removably secured within the stock, said plug having a recess in the inner or rear end and a boss or hub carrying a detonating cap, of a pair of wings or jaws pivoted within the recess in the hammer, 95 means holding the free ends of the jaws in closed position, and means providing for the escape of air at either end of the hammer.

5. In a shell-fuse, the combination with a suitable stock, a spring-pressed hammer or 100 plunger seated therein, said hammer being provided with air-passages and having a recess in its forward end and a firing-pin projecting from said recess, and a plug removably secured within the stock, said plug having a recess in the inner or rear end and a boss or hub carrying a detonating cap, of a pair of wings or jaws pivoted within the recess in the hammer, means holding the free ends of the wings in closed position, and a lug projecting 110 into one of the air-passages, whereby the forward movement of the hammer will be slightly retarded while under the tension force of the spring.

6. In a shell-fuse, the combination with a 115 stock having a hammer-chamber and a priming-chamber, a hammer seated in the hammer-chamber, and a cap-carrying plug removably secured in the priming-chamber, of a pair of wings or jaws longitudinally pivoted on the 120 hammer movable therewith and transversely movable thereof, and means normally holding the wings or jaws in closed position, whereby accidental contact with the cap is prevented.

7. In a shell-fuse, the combination with a 125 stock having a hammer-chamber and a priming-chamber, a hammer seated in the hammer-chamber, and a cap-carrying plug removably secured in the priming-chamber, of a pair of wings or jaws pivoted on the hammer and 130

movable therewith, means normally holding the wings or jaws in closed position, and additional means normally locking said wings or jaws in said closed position.

8. In a percussion-fuse, the combination of a casing, a primer, means removably seated in the casing for supporting the primer, and a primer-exploding means, consisting of a plunger carrying a firing-pin therewith, and a plurality of wings or jaws longitudinally pivoted to the plunger and transversely movable thereof, whereby said plunger is normally retained against forward movement by the wings engaging with the primer-supporting means and released from such engagement when said wings are influenced by centrifugal force.

9. In a percussion-fuse, the combination of a casing, a primer, means for supporting the primer in the casing, a plunger carrying a firing-pin therewith, and means longitudinally pivoted on the forward end of the plunger to normally hold said plunger and firing-pin against forward movement, said means mov-

able transversely of the plunger and actuated by centrifugal force to allow the plunger to move forward and cause the firing-pin to explode the primer upon impact of the shell.

10. In a percussion-fuse, the combination of a casing, a plug carrying a primer removably secured in the casing, a plunger carrying a firing-pin, a plurality of wings longitudinally pivoted on the forward end of the plunger, said wings being interposed between said plunger and the primer-carrying plug to normally hold the plunger and firing-pin against forward movement, said wings movable transversely of the plunger and actuated by centrifugal force to allow the plunger to move forward and cause the firing-pin to explode the primer upon impact of the shell.

In testimony whereof I affix my signature in the presence of two witnesses.
